Primary Examiner — Lauren R Calve

(74) Attorney, Agent, or Firm — Mark D. Miller; Jared E. Christensen

(57) **CLAIM**

I claim the ornamental design for a clothing hanger, as shown and described.

DESCRIPTION

FIG. 1 is a front perspective view of a clothing hanger showing my new design;

FIG. 2 is a rear perspective view of the embodiment of FIG. 1;

FIG. 3 is a left side elevational view of the embodiment of FIG. 1;

FIG. 4 is a front elevational view of the embodiment of FIG. 1;

FIG. 5 is a right side elevational view of the embodiment of FIG. 1;

FIG. 6 is a rear elevational view of the embodiment of FIG. 1;

FIG. 7 is a top plan view of the embodiment of FIG. 1; and,

FIG. 8 is a bottom plan view of the embodiment of FIG. 1.
